UNITED STATES PATENT OFFICE.

JOSEPH MOSES WARD KITCHEN, OF EAST ORANGE, NEW JERSEY.

METHOD OF SAVING FUEL.

No Drawing.

Application filed June 17, 1924. Serial No. 720,650.

The general object of this invention, which pertains to the preburning preparation of fuels, is effecting conservation of fuels. Specifically, the objects are: To 5 overcome fuel wastes and to reduce the costs of fuels for generating heat for heating, for generating power, for gas making, and for other utilities. The invention is a sequence to other inventions of mine having fuel 10 economization for their purpose, for which patents have been granted to me; but over all of which, the present invention is an advance. Various of my copending applications relate to the preburning preparation 15 and improvement of crude fuels, as well as to improved methods of burning them.

The present invention is the outcome of my recognition of the fact that there is an economic desirability in effecting more or 20 less of a change in the physical character of a large part of crude coal deposits before their burning; because all coal deposits have at least some natural defects which interfere with their economic use. Most deposits 25 have marked physical defects. The vast fields of lignite have an excessive water content. Bituminous coals have an excessive content of solvent volatile. Some hard coals such as the Massachusetts and Rhode Island 30 graphitic deposits, have so little volatile content that it is practically impossible to burn them alone in their natural state. The bituminous and lignite coals have the defect of swelling and crumbling or slacking under 35 mechanical handling and atmospheric or other heating influence; and even the best anthracite coals have the defect of so large an ash content, so that in their use the fuel 40 particles become externally coated with air excluding ashes during their descent thru fuel-beds; which coats largely prevent the complete combustion of the fuel-particles. The result of this peculiarity is, that about 45 one-half of the bulk of anthracite ashes is composed of unburned carbon in the form of cinders that are shaken thru grate openings. The present invention materially overcomes the defective character of crude 50 soft coals, by so treating them that fuel-masses of the prepared coals will be so hardened and of retained porosity as to allow air and other gases to pass thru the fuel-masses during their burning; yet the hard-

ened prepared fuel-masses will have a desirable B. t. u. concentration of heat producing energy per unit of bulk. Also, that such prepared fuel-masses will not become excessively compacted and clogged in use thru their crumbling and slacking in their burning; nor will melt, fuse and form irregular 55 non-uniform surfaces and masses of coke or slag, or form air funnels in the fuel-bed, or otherwise permit excess volumes of air for combustion to pass thru the fuel-bed and dilute the heat of the burned gases of combustion. The smokeless combustion of fuels that naturally are smoke forming is an object of this invention.

In carrying out the main aim of the invention, I preferably first secure material 70 for the formation of a juxtaposed matrix or frame of fuel particles that will be sufficiently hard in texture to prevent such compaction in their burning as always occurs in crude, natural, unchanged forms of soft 75 coals if used alone and uncoked in fuel-beds; and also, that will be sufficiently hard to largely resist the impacting pressure of such softer crumbling or slacking fuels that may be intermixed with the harder fuel particles. This juxtaposed pressure-sustaining, hardened matrix is of a character that requires greater heat to volatilize than any B. t. u. enriching interposed admixed solid 80 soft fuel or than enriching fluid impregnants that I may use in preparing such fuels. Hence, the harder constituents require a longer time to burn. This fact necessitates providing for the burning outside of the 85 fuel-bed of some low temperature volatilized 90 matters, produced in the fuel-bed.

I may use for the fuel-mass-matrix or frame, hard uncoked fuels such as the Massachusetts and Rhode Island graphitic coals that are not usable alone, because of 95 being deficient in volatile content. I may use ordinary anthracite for the matrix, altho in the larger sized grades, that fuel is usually too expensive to be economically available. For some uses I intermix small sized 100 low cost anthracite grades with hard anthracite, graphitic or hard cokes of larger sizes, for purposes hereafter explained. Preferably, I use as a matrix, coke produced from bituminous or lignite coals, because of 105 their richness in volatile, which volatile in

the preparation of my fuels, becomes transformed into valuable by-products in the form of burnable gases of various thermic values, tar, and ammonia products. In 5 preparing a coked basis of my fuels, I may use high temperature carbonization, and drive off substantially all the volatilizable matters; for in doing so, it is more easily to thereafter enrich the coked basis of the fuel- 10 mass with a determined desirable content of concentrated heat-enriching constituent. Such high temperature cokes have a special value for use as absorbers and holders of low cost fuel oil impregnants for use in the 15 generation of fixed burnable gases. Cokes of all degrees of hardness impregnated with fuel oil enrichers, have some value for burning completely for heating, and in generating steam. The use of low temperature carbonized coke is a part of this invention. Such low temperature carbonized cokes, 20 have considerable value for generating producer gas, or for oil gas, and for other purposes. In preparing my fuels, the methods 25 I use very materially facilitate the production of various cokes for various purposes. My copending application Ser. No. 697,769, describes a combined method of producing cokes of various characters, and their use in 30 generating burnable gases of various thermic values. Such prepared fuels are part of the present invention; for by coactive action in central plants thru gasifying the volatile in low cost coals I prepare a fuel- 35 gas of valuable character; I also utilize the heat of red hot coke in making water-gas. And by simple enrichment of the cokes, I secure a smokeless solid fuel, valuable for all heating purposes. By such coactive ac- 40 complishment I exercise such aggregate economies, that I prepare a fuel-gas of such low cost, that it can be used in internal combustion engines to generate power in successful competition with steam power; and 45 also, secure hard fuels that will accomplish substantially equal results with all natural hard fuels in all household heating plants, in electric lighting, and other economic results that need not be mentioned. The 50 present invention therefore is a component part of that aggregate complex invention, which is of great aggregate economic value.

In applying the principles of the present invention, I follow to some extent, the principle used in the Bessemer method of steel production, in which all the carbon is burned out of the molten iron, and then enough carbon is restored to the iron to secure the hardening effect required for steel 60 production. In the present invention, after hardening the basic framework of my fuel-masses, I reconstitute in the particle or in the mass, more or less volatile that is desirable as an equivalent with what has been removed from the crude fuel in the harden-

ing, coking process. This reconstituting practice is not to the extent of incorporating volatile diffusive matters in or with coked particles, other than what may be absorbed into the coke porosities if oily enriching impregnants are used. Such fluid impregnants, or admixed solid uncoked particles rich in volatile, become vaporized or volatilized at lower temperatures than those required in the burning of such fuels, which fact calls for carrying out the practices in preparing and burning such fuels which are herein described. 70

In adding an enriching solid content to my basic fuel-matrices, I preferably use 80 comminuted bituminous small particles, or slack that in its slackening, has acquired a relatively permanent form, as well as because it is low in cost. An important economic feature of my invention is, that I use 85 low cost fuels that have relatively little demand, and hence can be purchased at low prices. If I use unslackened bituminous semi-bituminous or lignite coals to admix with harder coked or uncoked fuels, I prefer- 90 ably mechanically comminute the unslackened soft or semisoft fuel, and if I do not use coke for the basic hard matrix of the juxtaposed fuel-mass, I add some coked smaller particles with the enriching soft bituminous 95 particles in order to maintain a sufficient porosity in the fuel-mass, as well as to secure heat engendering intensity in burning harder uncoked fuels that may be lacking in volatile content. 100

The amount of soft coal slack, or other ungraded fuels of small particles rich in volatile, that I may admix with larger sized coke or hard coal particles, depends upon the use to which the fuel is to be applied. 105 For steam generation in which I preferably use mechanically forced draft, and which I describe in several of my copending applications, the proportional amount of admixed bituminous particles I use, may be larger 110 than if the fuel-mass is to be burned with a less intense, and nonuniform naturally induced draft. The depth of the fuel-bed used may also determine the amount of enrichment of the coked matrix. I avoid admixing 115 so many small soft particles in the interstices of the juxtaposed large particles as will interfere too much with the draft tho in shallow fuel-beds thru which I mechanically force a draft, the entire interstices be- 120 tween the coke matrix may be filled with bituminous or lignite slack. In such instances, large amounts of low cost fuels of the smaller sized grades can be used economically, if due care is taken to burn outside of the bed, all 125 the burnable gases that are forced out of the fuel-bed by the mechanical draft. When I use fuel-dust in my admixtures to prevent flying dust and cinders in their use, I prefer to moisten the dust with water before admix- 130

ing it with the coal particles of larger size; but I do not moisten the larger coke particles with water unless I use the fuel for "banking" purposes. I may moisten the dust 5 with fuel oils for special purposes.

The admixing of the coked and uncoked fuel particles, I effect in any known way. For various uses, I have found that admixtures of one-quarter to one-third of the bulk 10 of the fuel-mass of small sized uncoked bituminous particles, to two-thirds of the bulk of the coked particles, usually burns well without smoke. I vary the depth of the fuel-bed according to the use to which I apply the 15 fuel, and according to the size of the fuel particles. I preferably maintain such depth of the fuel-bed that no excess air for combustion can pass thru the fuel-bed under ordinary drafts; but I provide for the combustion of any unburned gases that escape 20 from the fuel-bed, whether I use induced or mechanical draft, or both, in the burning of the fuel.

In igniting a fuel-bed of my prepared 25 fuel, I may use a substratum of coke that has been impregnated with an inflammable hydrocarbon. I sometimes moisten anthracite dust with a fuel oil, and use that in place of bituminous slack, in fuel admixtures. In 30 that case, care must be taken in not firing too large a mass at one time of such oil enriched fuel. It may however be fed gradually, especially if fed onto and burned on a chain grate.

35 It will be understood that the fuels herein described and claimed are as a rule those which are mostly intended for complete burning in situ, and not for intentionally making producer gas, altho it is difficult, if 40 not impossible, to prevent the formation of some producer gas in every fuel-bed, which gas escapes from the fuel-bed unless sufficient air for the combustion of the gas is passed entirely thru the fuel-bed or introduced above the fuel-bed. I aim to prevent 45 the passing of excess air thru the fuel-bed, thru preparing the textures of the fuel-masses, the depth of the fuel-bed, and the controlled amount of air that is allowed to 50 pass into, or that is forced thru the fuel-bed. It is important to provide for the complete burning outside of the fuel-bed of any burnable gases that may pass out from the fuel-bed. I use low temperatured carbonized 55 cokes in mixtures for generating producer gas.

60 Inasmuch as the present invention has for an aim, the complete burning of the fuel-mass, and as the utmost direct radiation of heat from the burning of the fuel-mass into impacting contact with heating surfaces is desirable, it follows that the maintained physical character that is desirable in the fuel-mass, is also important, as well as the 65 method of its burning. It is desirable to se-

cure an equalization of the rate of combustion thru the maintenance of uniformity in the texture of the surface of the fuel-bed as well as its depth; and when possible, the maintenance of a horizontal plane of the 70 fuel-bed surface. This character in the fuel-bed I largely secure thru the juxtaposed contact of hard, slow burning matrix-particles of the fuel-bed, a large part of the heat generated in the fuel-bed being produced at the 75 higher levels of the fuel-bed from smaller particles of richer and more quickly burned fuel-particles interspersed between the juxtaposed harder particles of the fuel-bed. This leaves an increased porosity of the fuel- 80 bed at lower levels.

Inasmuch as I preferably admix with coked fuel, soft coal particles that have already become slackened or have been mechanically comminuted, my prepared fuel 85 maintains a less changeable physical character than is possible if unslackened or uncomminuted fuel particles are used. The election of size of particles not only prevents the compaction of the soft fuel, which 90 occurs if unslackened and non-comminuted soft fuel particles of larger size are used. It also maintains a more equable character of porosity in the fuel-mass as a whole. As the soft particles are volatilized mostly in 95 the upper levels of the fuel-bed, the lower levels of harder character maintain a more open porosity which permits adequate access of air to and the complete combustion of the harder fuel particles at the lower levels. 100 This prepared fuel may be intermittently fed in blanket layers over the top surfaces of fuel-beds, and this acts mechanically to secure a high combustion temperature at lower levels of the bed, with comparatively 105 little opportunity to generate CO gas in the upper levels thru a recessive change of the CO₂ formed in the lower levels, which recessive change is so great a cause of losses in fuel-masses composed entirely of hard 110 anthracite graded coals having a uniformly diffused content of volatile, burned with draft entirely thru the fuel-bed, which diffused content in moderate presence in the fuel is the reason for the smokeless burning 115 of anthracite coal. In my copending application Ser. No. 717,197, filed May 31, 1924, I describe a dumping pit, into which partly burned coked fuel particles that have traveled over a chain grate, are dumped and 120 are entirely burned in a fuel-bed so deep as to prevent excess air passing thru the fuel-bed, in conjunction with a controlled admixture of air for combustion in the combustion space above the fuel-bed. This is a 125 minor detail that however is important in securing the best economic results in saving fuel.

I emphasize the fact that I preferably use coked fuel particles of relatively large size 130

with ungraded smaller fuel particles occupying part of the interstices of the juxtaposed larger sized fuel particles. This juxtaposed contact of the particles largely prevents 5 clogging impaction of the softer smaller particles that are intermixed with the larger particles. I not only use fuel-beds of such depth that excess air for combustion cannot readily pass thru the fuel-bed, but 10 I also use mechanically forced draft to force air for combustion into the fuel-mass in proper amounts, and for admixing proper amounts of air for combustion with such unburned burnable gases as escape from the 15 fuel-bed. I also control the pneumatic pressure in the gas burning combustion spaces in which I burn gaseous fuel, as well as the rate of travel of the burned gases over the heating surfaces; and preferably do so, by 20 more or less obstructing the burned-gas-exit-aperture from the combustion space, as well as aim to secure a complete combustion of the gases at a level considerably below the heating surfaces. I may prepare fuels for 25 generating producer gas thru the use of uncoked very hard graphitic coals, in admixture with more or less enriched coked particles, and in such proportions as to secure a desirable circulation of gases thru the 30 fuel mass in the producer gas generator. I secure the aim of controlling the porosity of the fuel mass in the producer generator thru an obstructive admixing fine of anthracite dust and bituminous slack with coke in 35 such proportions as will secure by obstruction of the particles the heat necessary to gasify the very hard uncoked coal and the coke, in conjunction with a controlled forced draft, or maybe with a controlled obstructed 40 closure of the exit aperture for the gas from the producer. I prepare a "blanketing" fuel, by utilizing low cost hard fuels admixed with fine coal dust or coke breeze or both, and thoroughly wetting such admixtures. 45 It should be noted that I use a large variety of fuel materials in forming my fuels, that may be hard or soft in character; and that the particles used may all be ungraded, or partly graded and partly ungraded. If a 50 coked matrix is used, I partly rely on the porosity of the coke to pass draft thru the fuel-mass, except when I impregnate the coke with fuel oils, in which case I generally do not admix naturally rich soft coal particles with the oil enriched coked particles. 55

In the present invention I do not broadly claim the idea of having originated the mixing of fuels; but I do claim specifically, certain mixtures of fuels having special use in 60 certain instances; which use will effect fuel economies, and other advantages that hitherto have not been secured in the art of fuel economization, especially when such admixed fuels are inventively combined with the 65 methods of their preparation and burning.

For example; at the time of this writing, a strong effort is being made to burn low cost small sized buckwheat and smaller sizes of low cost anthracite fuels, by the use of mechanical draft forced thru the grate, and upward thru the fuel-bed. There is always a superabundance of such small sized grades of anthracite fuels in connection with anthracite mines. Effort has been more or less successfully applied in burning such 70 small sized fuels on grates of special construction; but to burn them on grates having the usual sized grate openings thru which ashes can be easily shaken, it has been necessary to depend on the formation of a 75 mat of combined ash and melted fuel particles located at a level above the grate line, that will prevent the small sized particles from sifting thru the grate. This operation requires the application of special skill, a 80 skill that is not possessed by the average furnace attendant. To overcome that trouble, I admix a portion of larger sized particles of anthracite or hard coke with the smaller sized particles of anthracite. The 85 larger sized hard particles take longer time to burn than the smaller sized particles, and in the burning of the larger sized particles they gravitate to the grate line only partly burned, and form a supporting platform 90 onto which the small particles that may not be burned, are intercepted and are burned on that platform without sifting thru the grate. Hence, my idea is of considerable 95 economic value, and a fuel mixture of that 100 character is based on an inventive patentable idea.

In claiming specific fuel mixtures of various kinds and of various sized fuel particles, it must be understood that when I claim 105 particles of fuel of relatively large size in combination with fuel particles of relatively small size, I do not restrict myself to any particular size or grade of either size of particles. Such limitation is not essential. The 110 essential matter is that in case of hard coked particles enriched with uncoked small sized particles of soft coal rich in volatile, that the constituent amount of the admixed small sized soft coal, is less in its aggregate bulk, 115 than the bulk of coke or hard coal; for in that case, in the burning of the soft coal particles, they will not entirely fill the interspaces between the hard particles and thus clog and obstruct or entirely prevent 120 the passing of gases thru the fuel-mass. If the particles of coke or other hard coals in the mixture, are equal or smaller in size than the soft coal particles or in lesser bulk amounts, the crumbling and melting of the 125 soft coal particles more or less clog or entirely obstruct the passage of draft thru the fuel-mass; the consequence of which is: smoke formation or entire stoppage of combustion in the fuel-mass. This is especially 130

so in connection with the use of natural induced drafts when applied to open grates or deep fuel-beds occupying enclosed fire-boxes. In thin fuel-beds, smaller proportions of coke can be used if mechanical draft is forced upwardly thru the fuel-bed.

In the ordinary method of burning particles of soft coals effectively, the crude particles are continually introduced into the zone of combustion and coked on traveling grates or in under-feed devices; but in either practice, a very considerable portion of the volatile that is driven off from soft coals, is generally lost. In my invention an advance is claimed in the present and in my eight other copending applications, of making the coking of fuel a separate operation, and utilizing the driven off volatile in producing fixed burnable gases of determined commercial value, as well as having a more cleanly condition; in which cleanly state the fuel-gas has an increased commercial value for use in the internal combustion engine in generating power, as well as for use as a gaseous fuel to be applied in domestic practice in cookery, and in some cases, in burning in heating devices.

In this combined practice, there is gained a large reduction in the cost of power as compared with its generation thru burning coal under steam boilers. In the future, applicant believes that substantially all power will be produced by the burning of prepared low cost fuel-gases in gas engines; while most of heating operations in large buildings will be effected by the burning of prepared solid fuels having as a framework or basis, hardened cokes more or less enriched with low cost raw soft coals either accidentally slacked or mechanically comminuted into such sizes that in their intermixture with hard coals or coke of larger size that are in more or less juxtaposed contact, the small enriching particles will only occupy a part of the interstices of and are prevented from compaction by the juxtaposed contact of the larger sized hard particles.

A modification of the applied principles of this invention is the admixture of hard particles of coal of various graded sizes which are burned by intermittent applications of the admixed hard fuels of various sizes, applied in successive coats onto the top surfaces of fuel-masses. There are large amounts of small sized anthracite coals such as buckwheat or smaller sizes, that can be efficiently burned in ordinary fuel burning devices constructed to burn deep beds of fuel that have ordinary grates already in existence. By adding to such small sized hard particles a minor bulk of hard coal or coke of larger sized particles, even with the use of induced draft, a considerable amount of the smaller sizes and lower cost grades

can be utilized, and without the use of a mechanical draft. If forced mechanical draft is used, a larger amount of the small sized particles can be used in admixture with various bulks of hard large sized particles which gravitate to the grate, while the smaller sizes are burned in the middle and upper zones of the fuel-bed, and their sifting thru the grate is prevented on that account. Applicant believes that this is an entirely new practice in connection with the art of fuel conservation and hence, that claimed fuel mixtures suitable for that particular use, are patentable and allowable to applicant.

There are large deposits of graphitic fuels that have slight or no volatile content, that can be utilized in the mixtures herein described and claimed. Such coals will burn if under a surrounding influence of sufficient heat, such as in the lower zones of fuel-beds having admixtures of fuel particles containing sufficient heat engendering volatile.

In certain mixtures I secure the enrichment of cokes with impregnated low cost fuel oils. The latter enriched cokes, are of value in generating gas, as hardened cokes withstand without crumbling, the heat of the interior of gas retorts, while the impregnating oil is volatilized and gasified without gasification of the impregnant holding coke. In this case, the porosity of the gas producing fuel-charge is maintained, and there is little or no carbonization on the interior surfaces of the retort.

In speaking of fuel particles of relatively small size, I usually mean, of considerably smaller size than the particles of hard coal; but I definitely state here that such admixture may be of hard particles of a size larger than chestnut sized grades and of smaller particles smaller in size than chestnut sized grades. In my banking fuels, in which blanketing coats are added to ignited fuel-beds, I designedly add crushed comminuted sizes of coke of any graded or of ungraded sizes, inasmuch as all of such fuel particles are hard, burn slowly, and can be fully impregnated with water, and help repress combustion. Some of the accompanying claims relate to this particular class of mixed fuels. It will be understood that the character of the various mixtures specifically claimed is suitable for various purposes.

The use of cokes of various degrees of carbonization in fuel mixtures, is of economic value for various purposes, in various proportions, in various mixed fuels. Those which I claim in this application are of special value. Mixed fuels having coke of various sized particles and in various proportions, are specifically useful in giving porosity to fuel-masses, and for reducing excessive volatile content in fuel-masses as a

whole; but if used alone and if produced by high temperature carbonization, they are too porous, too incombustible and are lacking in desirable volatile content for ordinary purposes of engendering heat, although they have useful value for metallurgical work.

I emphasize the fact that in the fuel mixtures in which I ordinarily use coked particles of fuel of relatively large size as an important constituent of my fuel-masses, I use smaller particles of soft uncoked coals of smaller size; and especially do so in soft coal districts. I may however in other instances replace coke with hard graphitic, or anthracite large sized particles, and use small sized low cost hard anthracite particles, in forming fuel-masses. I particularly in some cases, use anthracite buckwheat, or smaller grades of anthracite, in place of uncoked bituminous or lignite particles. Wherever such anthracite low cost fuels are available, they are usually preferable to utilize in place of soft bituminous or lignite small sized particles. The character of the fuels I use varies as to their place of origin, and largely depends upon their abundance or scarcity. Inasmuch as the soft coals are in very much greater abundance than hard coals having limited desirable volatile content, their use would naturally follow in districts where the soft fuels are plentiful, and then I would use coke in place of hard anthracite for the larger sized particles. On the other hand, in the regions where the graphitic coals exist, they can be used with economic advantage in place of coke.

But I wish to also emphasize the fact, that where coke is abundant, it can be used advantageously to a large extent in many fuel mixtures, especially in connection with mixtures suitable for producer gas manufacture and for "banking" fuels. For the latter, I may crush large sized coke particles and use the crushed material intermixed with the fine dust of the harder coals and with some admixture of relatively large sized hard coal particles; the entire mixture to be well saturated with water. Mixtures of that character act very advantageously as "banking" fuels to use in domestic practice.

The proportionate amounts of large size and small size fuel particles that I admix, vary according to the graded size required for special purposes, as for example: cooking, furnace use, "banking", steam generation, and gas making. Also, as well as according to the force of the draft used, whether natural-induced draft, or forced mechanical draft. Also, whether the fuel is to be partially coked on the fuel-bed, and whether the grates used are stationary or of a traveling character. In case of the continuous feeding of the admixed fuel onto a fuel-bed, the uncoked soft constituent of the

admixtures may have a much larger proportion of soft small sized particles used. If there is to be no fuel-bed coking of the admixtures, it is preferable to have the smaller sized particles of the admixtures to be of low cost graded smaller sizes, or mixed screenings, or the dust of hard anthracite coal; all of which are low in cost.

In illustration of one form of admixed fuels I use, I cite: A fuel composed of admixed particles of coke and uncoked soft fuel containing a high volatile content; the coke constituent comprising particles of relatively large size, and the uncoked constituent comprising smaller sized particles than the large sized coke particles. In burning such a mixture, by feeding a relatively thick coat of the mixture on the fuel-bed, the mixture burns mostly from the under surface of the coat. The soft fuel burning first, leaves interspaces between the coke particles, and this allows for the passage of gases sideways to and outside of the borders of the newly fed coat of mixed fuel; and the gases and flame resulting from burning the under part of the newly fed coke, find more immediate contact with heating surfaces than if the passage of gases were altogether vertically up thru the newly fed fuel.

In these mixtures I have found it desirable to sometime change the character of the constituents to effect beneficial results in their burning. For instance, by mixing coke, high volatile soft coal and anthracite dust, the high volatile melts and incorporating the anthracite dust in the melted volatile, causes the volatile and dust to adhere to the coked particles. This is largely due to the capillary action of the coke. The effect is a quicker opening up of porous places between the fuel particles in the fuel-bed, and more quick and complete burning of the adherent constituents. In case of gasifying such mixtures in a gas-retort free from air, the same process occurs thru the effect of heating the retort, and when such adherent material is cooled either by steam or water, a useful form of fuel is the result, which is more brittle than high temperature coke, and also comprises enriched burnable matter to a higher degree than the basic coke used.

What I claim as new is:

1. A mixed fuel composed of prepared hard coal particles of relatively large graded size, and moistened coal particles of smaller size, the smaller sized particles being relatively rich in volatile and occupying only a portion of the interstices between the large sized particles.
2. A fuel composed of coke of graded large sized particles thoroughly mechanically admixed with uncoked coal of smaller sized graded particles.
3. A fuel composed of particles of coke in juxtaposed contact, and uncoked coal

richer in volatile than coke occupying part of the interstices of the particles in juxtaposed contact.

4. A thoroughly mechanically mixed fuel-
5 mass composed of unground coarsely
crushed coke of various sized particles, and
enriching uncoked fuel, said enriching un-
coked fuel having a higher volatile content
than the coke, said mass having gas pass-
10 ing spaces in the interstices between the
coke particles in the fuel-mass for the pas-
sage of draft thru the fuel-mass.

5. A composite fuel comprising graded
15 uncocked particles of coal of relatively large
size, and ungraded particles of coal of smaller
size, said large sized particles being in
juxtaposed contact and the uncoked par-
ticles of smaller size occupying only a por-
20 tion of the interstices between the particles
of larger size.

6. A composite fuel-mass comprised of
completely moistened and mechanically thor-
oughly admixed hard coal particles of rela-
tively large size, coke particles of smaller
25 size, and particles of uncoked coal dust.

7. A fuel-mass consisting of a matrix of
hard pressure-resisting coal particles of sub-
stantially uniform graded size, said parti-
cles being in juxtaposed contact, and un-
30 graded uncoked coal particles of smaller size
than but richer in volatile than the hard
coal particles, said uncoked coal particles
occupying a portion of the interstices of the
hard pressure-resisting matrix.

25. 8. A fuel-mass composed of dry particles
of coke of relatively large size, having mois-
tened coal dust adhering to the surfaces of
the coked particles.

9. A "banking fuel" composed of admixed
40 hard uncoked relatively large coal particles,
coke breeze, and anthracite coal dust, all of
the constituents of said "banking fuel" being
thoroughly moistened.

10. A fuel-mass composed of relatively
large sized graded hard coal particles in 45
juxtaposed contact, and soft coal particles
rich in volatile admixed with coked parti-
cles, said admixed soft coal particles rich
in volatile and coked particles substantially
fully occupying the interstices between the 50
hard coal particles.

11. A fuel-mass composed of a juxtaposed
matrix of large sized hard coal particles de-
ficient in volatile content, and admixed there-
with, mixed uncoked soft coal and coked 55
coal particles of smaller size than the hard
coal particles, the smaller sized admixture
occupying interstices between the hard large
sized particles.

12. A composite fuel-mass of high tem-
perature carbonized coked particles of coal
of relatively large size, and smaller sized
60 graded uncoked particles of coal interstitial-
ly placed between the coked particles of
large size, the particles of smaller size oc-
cupying only a part of the space between
the high temperature coke particles and be-
ing unchanged in their crude volatile con-
tent but having a B. t. u. content greater
than the B. t. u. content of the coked par-
70 ticles.

13. A fuel-mass composed of coke of rela-
tively large size, high-volatile bituminous
coal of relatively small sized particles, and
75 anthracite dust.

14. A fuel-mass composed of admixed
particles of coke breeze, particles of an-
thracite coal of a graded size larger than
rice size, and anthracite dust, said mixture
being thoroughly moistened with water. 80

15. A fuel-mass composed of admixed
particles of relatively large sized coke, par-
ticles of high-volatile bituminous coal, and
anthracite dust.
